(57) CLAIM

The ornamental design for an insulated attic access cover folding stairway, as shown and described.

DESCRIPTION

FIG. 1 is a perspective view of the invented insulated attic access cover folding stairway, showing my new design as installed in an attic access hatchway, the hatchway framework and folding stairway shown in broken lines;

FIG. 2 is a top view thereof;

FIG. 3 is a left side view thereof;

FIG. 4 is a right side view thereof;

FIG. 5 is a rear view thereof; and,

FIG. 6 is a front view thereof.

The broken lines showing portions of the hatchway framework and folding stairway are for illustrative purposes only and form no part of the claimed design.
